UNITED STATES PATENT OFFICE.

JOSEPH W. PIATT, OF NEW YORK, N. Y.

GAS-HEATER.

1,352,473.

Specification of Letters Patent. Patented Sept. 14, 1920.

Application filed November 30, 1917. Serial No. 204,710.

To all whom it may concern:

Be it known that I, JOSEPH W. PIATT, a citizen of the United States, and a resident of the borough of Manhattan, in the city, county, and State of New York, have invented certain new and useful Improvements in Gas-Heaters, of which the following is a specification.

This invention relates to gas heaters, particularly adapted to heat water for a hot water supply or for the generation of steam, and it is the primary object of the invention to improve the general construction of heaters of this character to reduce the consumption of gas or fuel and at the same time increase the heating efficiency of the heater.

In heaters of this character a tubular water unit is provided with a heat retaining jacket to inclose said unit and a gas burner is placed below said unit with the combustion chamber between said unit and the burner. As is well known for the proper combustion of gaseous fuel it is necessary to provide a secondary air supply at the point of combustion or the burner ports, and heretofore to supply such air the bottom of the heat retaining jacket has usually been left open. However, in the use of a heat retaining jacket it is necessary to provide means whereby the products of combustion may be carried off in order that the same will not be expelled into the room or other place where the heater is located, and for this purpose it has in the top an outlet which is connected to a flue, such as a chimney. As thus constructed there is a flue formed through the heat retaining jacket with the result that a considerable portion of the heat is carried off with the products of combustion, thereby impairing the efficiency of the heater. Furthermore, in order to effect the proper combustion of the gas, it is essential that the supply of secondary air be in proper proportion, as to supply too much air is just as inefficient as an insufficient supply.

It is an object of the invention to overcome the above disadvantages and to provide a secondary air supply chamber having an outlet leading into the combustion chamber adjacent the point where combustion is taking place and to provide means to regulate the flow of air through said chamber to the combustion chamber.

Other objects and advantages will herein-after appear.

In the drawings accompanying and forming a part of this specification Figure 1 is a sectional side elevation of a heater with an embodiment of my invention applied thereto.

Fig. 2 is a sectional plan view taken substantially on the line 2—2 of Fig. 1; and

Fig. 3 is a sectional plan view to illustrate the means to control the secondary air supply to the combustion chamber.

Similar characters of reference designate like parts throughout the different views of the drawings.

In the drawings I have shown an embodiment of my invention in connection with a heater comprising a heating or water unit, shown as a series of vertical tubes 4, connected at the lower ends to a water supply and in circuit with a water or steam circulating system by a pipe 5 through a head 6, and connected at the upper ends to a similar head (not shown). The top and sides of the heating or water unit are inclosed by a jacket 7 supported upon a base 8 and which may also serve to support the heating unit, with the bottom of the jacket communicating with said base and having an outlet flue 10 at the top for the escape of the products of combustion.

A burner 11 is supported upon an annular flange 12 within the base by brackets 13, 14 and has a gas fuel inlet 14' controlled by a valve 15 through a mixing chamber 16. This burner is of the type commonly known as a "tangential burner," the fuel or gaseous mixture entering the burner chamber or chambers in a line tangent to the burner, and is of the type disclosed in my co-pending application filed Nov. 10, 1916, Patent No. 1,267,448, granted May 28, 1918, in which the burner has a series of concentric chambers with air spaces, as shown at 17 in Fig. 2, between the respective chambers.

For the proper combustion of gaseous fuels it is necessary to provide a suitable air supply to mix with the gas which is usually supplied through a mixing chamber as shown at 16. However, to increase the combustible efficiency of such mixture a proper secondary air supply must also be provided to the combustible gases at the point of combustion or the burner ports, and this air supply must be in proper proportion to the gas, too great a supply of air being as inefficient as an insufficient supply. For this purpose I provide a secondary air cham-

- ber 18 within the base, said chamber being substantially of truncated cone shape, open at the top and bottom, that is, the walls diverge from the top, as clearly shown in Fig. 5 1, the opening at the top being adjacent the top of the burner with the walls spaced therefrom, as shown at 19, to provide an outlet for the air chamber adjacent the burner ports or about the combustion chamber.
- 10 An annular wall 20 extends downward from the jacket 7 and converges toward the top of the burner, where it is connected to the air chamber, or it may constitute a part of the wall of this chamber, the wall 20 forming a combustion chamber between the burner and the heating unit.
- 15 The flow of air through the secondary air chamber through the outlet 19 and burner spaces 17 to the combustion chamber 20 is controlled or regulated by a valve or shutter 21 in the form of a plate to conform to the contour of the inner wall of the secondary air chamber and located adjacent the bottom thereof to serve as a closure for the bottom of such chamber and adapted to be adjusted to provide a space between the lateral edges of the plate and the walls of the secondary air chamber for the passage of air to said chamber. To adjust the plate to regulate this space to increase or decrease the area thereof the plate is mounted to have vertical adjustment. Thermostatically operated means are provided to automatically adjust this valve 30 or plate to regulate the air inlet to the secondary air chamber and comprises a thermostat (shown in a general way at T) connected in the circulation of the heater and operatively connected to the plate by an angle lever 22 one arm of which is connected to the thermostat, as at 23, and the other arm connected by a link 24 to one end of a lever 25, the other end of the latter lever being connected, as at 26, to a lever 27, the other end of said latter lever being connected to the plate, as at 28, and the plate having a stud 29 by which it is slidably supported in the bracket 14, a spring 30 normally urging the plate downward.
- 35 40 45 50 To supply air to the secondary air chamber from the exterior of the building in which the heater may be located, a closure 31 is provided for the bottom of the air chamber having an inlet 32 to which a pipe 33 is connected leading from the exterior of the building, and which pipe may also serve to supply fresh air to the mixing chamber 16 by connecting said chamber through a pipe 34 with the pipe 33. To permit of adjustment of the burner the opening 35 in the base through which the burner inlet extends is enlarged, but is at all times maintained closed by a collar or plate 36 carried by the tubular inlet of the burner.
- 60 65 It is well known that by heating air it

will more readily mix with a gaseous fuel and produces a better combustible mixture, and by the provision of the air chamber 18 said chamber also serves as a heating chamber for the air which enters at the bottom, 70 and as it passes from said chamber to the combustion chamber through the outlet 19 adjacent the burner ports it will be heated to such a degree that the air will expand whereby the elements of the air are more 75 readily taken up by the flame or burning gaseous mixture and enable the burning gas to absorb the final oxygen necessary for complete combustion from a comparatively small amount of secondary air thus reducing 80 the dilution of the burning gases by excess secondary air.

Having thus described my invention I claim:

1. In a gas heater, the combination of a 85 combustion chamber; a burner at the base of said chamber; a secondary air chamber the wall of which extends around and downward from the top of the burner; the walls of said chamber diverging from the top to 90 the bottom and having an outlet adjacent the burner ports; a plate supported at the lower end of the air chamber to have adjustment in a vertical direction with the lateral edges spaced from the walls of the chamber; and 95 means to adjust the plate to increase or decrease the space between the lateral edges of the plate and the walls of the air chamber, substantially as and for the purpose specified.

2. In a gas heater, the combination of a 100 combustion chamber; a burner at the base of said chamber; a secondary air supply to the burner consisting of a chamber the wall of which extends around and diverges downward from the top of the burner adjacent the burner ports and spaced from the wall of the burner to constitute an outlet of said chamber adjacent the burner ports; a plate supported at the lower end of the air chamber 105 to have adjustment in a vertical direction with the lateral edges spaced from the walls of the chamber; means to normally urge said plate downward; and means to adjust the plate upward against said latter 110 means, substantially as and for the purpose specified.

3. In a gas heater, the combination of a 115 combustion chamber; a burner at the base of said chamber; a secondary air chamber the 120 wall of which extends around and diverges downward from the top of the burner, with the wall of said chamber spaced from the wall of the burner adjacent the burner ports to constitute an annular outlet for the chamber and an inlet to the bottom thereof; and a plate at said air chamber having a space between the lateral edges and the walls of the air chamber, said plate being vertically 125 adjustable to increase or decrease said space 130

and thereby regulate the flow of air through said chamber to the combustion chamber, substantially as and for the purpose specified.

5 4. In a gas heater, the combination of a heating unit and a heat retaining jacket to inclose the same; a burner below said unit; an annular wall extending from the bottom of the jacket and converging to adjacent the 10 burner to provide a combustion chamber between the burner and unit; an air chamber

extending downward from the burner and having an outlet leading to the combustion chamber adjacent the burner ports and an air inlet; and means in said chamber to 15 regulate the flow of air through said chamber to the combustion chamber, substantially as and for the purpose specified.

Signed at New York city, in the county of New York and State of New York, this 2d 20 day of December, 1916.

JOSEPH W. PIATT.
